EDWARD H. ELDER, OF CHICOPEE FALLS, MASSACHUSETTS, ASSIGNOR TO NATIONAL BLANK BOOK COMPANY, OF HOLYOKE, MASSACHUSETTS, A CORPORATION.

LOOSE-LEAF BINDER.

1,024,472.

Specification of Letters Patent.

Patented Apr. 23, 1912.

Application filed January 31, 1911. Serial No. 605,785.

To all whom it may concern:

Be it known that I, EDWARD H. ELDER, a citizen of the United States of America, residing at Chicopee Falls, in the county of 5 Hampden and State of Massachusetts, have invented new and useful Improvements in Loose-Leaf Binders, of which the following is a specification.

This invention relates to loose leaf binders and especially to what is known in the art as a transfer binder, the object of the invention being to provide an improved device for locking the sheets transferred to the binder, and in certain details of construction incidental to this improved construction, all as set forth in the following specification and clearly summarized in the claims appended thereto,—the invention being illustrated in the accompanying drawings 20 in which,—

Figure 1 is a sectional plan view of a binder embodying the invention, the plane of the section being parallel with the covers of the binder and indicated by the dotted line 1—1, in Fig. 2. Fig. 2 is a sectional elevation of the binder, the plane of the section being at right angle to that shown in Fig. 1 and indicated by the dotted line 2—2, Fig. 1. Fig. 3 is an enlarged cross-sectional view of the binder taken on line 3—3, Fig. 1, showing the connection of the locking slides with the equalizing bar. Fig. 4 is an enlarged cross sectional view of the binder taken on line 4—4, Fig. 1, showing the 25 construction of one of the sectional posts and the relation of one of the locking slides thereto. Fig. 5 is an elevation of the right-hand end of the binder as shown in Figs. 1 and 2 and shows the end of the screw-rod 40 which actuates the locking-slides.

Referring to the drawing, the binder consists of the oppositely located parallel tubular parts *a* and *b* of metal, to each of which is attached a cover for the book of sheets to be bound therein, said cover being indicated by *c*, both upper and lower cover having the same indicating character, these being attached to the tubular parts *a* and *b* by a strip of leather or fabric *d* which incloses 45 the said tubular parts and is then extended to and over the cover and glued thereto both on the outer and inner sides thereof, all as customary in bindings of this character, this leather or fabric constituting a hinge for 50 the covers.

In the tubular part *b* and extending therefrom to and through the tubular part *a* are the posts *e* and *f*, consisting of several sections which are screwed one to the other endwise to build up a post to adapt the 60 height thereof to the thickness of the sheets to be bound in between the tubular parts *a* and *b*, that section of the posts located in the tubular part *b* being permanently secured to said part by riveting or otherwise, 65 the other sections being added as required. This too, is ordinary construction and well understood.

When sheets *g* of paper are to be inserted in the binder the tubular part *a* thereof and its attached cover are removed from the posts *e* and *f*, the sheets (suitably perforated) being fitted onto the posts, and the part *a* of the binder is then fitted over the posts and a suitable locking device in the 70 part *a* is used to lock said part to the posts until such time as more sheets are to be added to, or subtracted from, those in the binder. These locking devices are generally arranged to frictionally engage the 75 posts *e* and *f*, and have generally been so constructed as to throw the posts out of alinement in such a way that when sheets are to be inserted it is found that the ends of the posts do not register with the per- 80 85 forations in the sheets.

By means of the present invention the locking device, located in the tubular part through which the free ends of the posts *e* and *f* extend, is so constructed that pressure 90 to frictionally engage the posts is applied to each post in the same direction so that if the posts are deflected they will both be deflected in the same direction, and the distance between the ends will not be changed 95 to any appreciable degree, and thus no difficulty will be found in easily fitting over these posts any new sheets which it is desired to introduce in the binder.

The above referred to deflection of the 100 posts does not, as a rule, take place until after they have been considerably lengthened by the addition of one or more sections when the force applied thereto by the operation of the locking devices is applied 105 at some distance from the base of said posts, but frequently this deflection is very marked when the binder is nearly filled up.

The locking device for the part *a* of the 110 binder comprises the two flat metal arms *h*

and z , which extend from an equalizing bar m in which they are loosely pinned, as at o , on opposite sides of the center of said bar, and they extend in opposite directions, the 5 one indicated by h toward post e and the other one k , toward the post f . The post e extends through a hole in said arm h which is very slightly enlarged in the direction of the length of the bar. The other 10 arm k extends, as shown in Fig. 1, very nearly to the post f .

Between the points o where the bars h and k are pivotally secured in the equalizing bar, a screw-threaded rod p extends through 15 this bar, the opposite end extending through a hole in the block q which is pinned into the end of the part a of the binder, and serves as a closure for said end, the rod having also a threaded engagement with said 20 block. Preferably the threads on the bar m are right and left-hand threads.

The threaded hole through the equalizing bar m is made large enough to permit the rod to fit freely therein to the end that it 25 may fulfil its functions as an equalizing bar as it is obvious that a very close fit of the rod in said bar would not permit any swinging movement of one end of the bar relative to the other in case one of the arms h or k 30 should bring up against one of the posts in advance of the other. The end of the screw-rod p extends through to the end of the part a of the binder and is squared to receive a key r whereby it may be rotated to force the 35 arms h and k in the same direction to bring them into frictional contact with the posts e and f , whereby the tubular part a of the binder may be temporarily secured to said posts.

40 The holes through the removable tubular part a of the binder and through the arm h must be large enough to permit these parts to be easily fitted over the ends of the posts e and f , and this rather loose fit makes it 45 impossible, practically, to so proportion the two posts e and f that they will come to a bearing simultaneously against these parts when the rod p is screwed up. Hence, the equalizing bar m is employed and loosely 50 fitted on the rod to the end that whichever one of these arms may come in contact with the post in advance of the other arm, the latter, through the slight swinging movement of the end of the bar m in the direction of 55 movement of the arm pivoted thereto, will permit this arm to be moved by the screw-rod into contact with its post in a manner to bring both arms against their respective posts under equal pressure, which will be

applied to the posts in the same direction, 60 whereby if the posts are sprung, the distance between these ends will not be appreciably changed and no difficulty will be experienced in applying to the posts either the leaves to be bound in the binder or the removable tubular part a thereof.

What I claim, is:—

1. A loose leaf binder comprising two back members to which the binder covers are attached, metal posts fixed in one of said members at right angles thereto to receive perforated sheets of paper, said second movable member having holes therethrough whereby it may be fitted over said posts to bind the sheets of paper together, two 75 structurally separate locking slides in said movable member one to bear against each post, means loosely connecting the slides and means extending outside of said movable member to move the connecting means 80 whereby said slides may be moved against said posts simultaneously in the same direction.

2. A loose leaf binder comprising two tubular back members to which the binder 85 covers are attached, metal posts fixed in one of said members at right angles thereto to receive perforated sheets of paper, said second movable member having holes therethrough whereby it may be fitted over said 90 posts to bind the sheets together, locking slides in said movable member to bear against the same side of each post, said slides comprising movable arms extending lengthwise of said member, and whose inner 95 ends are adjacent one another; an equalizing bar to which said ends are connected, and means to actuate said bar in either direction lengthwise of said member.

3. A loose leaf binder comprising two tubular members to which the covers are attached, posts fixed in one member and extending loosely through the other, and a locking device in said second named back member to secure it to said posts, said locking device comprising two arms, an equalizing bar to which the inner ends of said arms are pivotally connected, and a screw rod threaded loosely into said equalizing bar between the pivoted ends of said arms whereby by the actuation of said screw-rod said arms may simultaneously be moved in the same direction against said posts.

EDWARD H. ELDER.
